W. L. ECKHARDT,
NEEDLE ARM FOR TALKING MACHINES,
APPLICATION FILED MAR. 11, 1916.

1,296,638.

Patented Mar. 11, 1919

UNITED STATES PATENT OFFICE.

WALTER L. ECKHARDT, OF PHILADELPHIA, PENNSYLVANIA.

NEEDLE-ARM FOR TALKING-MACHINES.

1,296,638.

Specification of Letters Patent. Patented Mar. 11, 1919.

Application filed March 11, 1916. Serial No. 83,475.

To all whom it may concern.

Be it known that I, WALTER L. ECKHARDT, a citizen of the United States, residing in the city of Philadelphia, county of Philadelphia, State of Pennsylvania, have invented certain new and useful Improvements in Needle-Arms for Talking-Machines, of which the following is a specification.

My invention has for its object to provide 10 an improved construction of needle arm (stylus or needle support) for sound reproducing machines, including means for adjusting the stylus or needle with respect to said arm or support.

15 A further object of my invention is to provide an improved construction of needle arm and stylus or needle by the use of which a single stylus or needle of attenuated wire may be used a great many times for the 20 production of sounds for sound records without injury to said records and also by the use of which the sounds reproduced shall be more nearly like the original sounds impressed upon the record than, as far as I am 25 aware, heretofore has been practicable.

30 A still further object of my invention is to provide a needle arm or support by means of which an attenuated or fine wire employed as a stylus or needle may be rigidly and firmly held so as to prevent a vibration of the same independently of said needle arm or support.

35 It is also an object of my invention to provide a needle arm having a fine or attenuated point adapted to enter the sound grooves upon a sound record whereby, if occasion should arise, the needle arm itself may be employed to coöperate directly with a sound record without or independently of 40 the stylus or needle for the reproduction of sounds from said record.

In the accompanying drawings I have 45 illustrated one form of a convenient embodiment of my invention but it will be understood that the same is susceptible of embodiment in other forms of construction within the scope of the claims.

In the drawings:

50 Figure 1 is a side elevation of a sound box having secured thereon and in operative relation thereto a needle arm and stylus or needle embodying my invention, the said figure also showing a portion of a record in

transverse section with which the end of the stylus or needle is in contact;

55 Fig. 2 is a view in front elevation of said needle arm and stylus or needle separate from the sound box and enlarged;

Fig. 3 is a view in side elevation of the same;

Fig. 4 is a view showing a portion of said needle arm in longitudinal section on the line 4—4 of Fig. 2;

Fig. 5 is a transverse sectional view taken 65 on the line 5—5 of Fig. 2;

Fig. 6 is a transverse sectional view taken on the line 6—6 of Fig. 2; and

Fig. 7 is a longitudinal sectional view taken on the line 7—7 of Fig. 3 in a plane at right angles to that on which Fig. 4 is 70 taken.

Referring to the drawing, 1 designates the small end of a tapered talking machine horn to which is connected a sound box 2. The casing of the latter is provided with projecting ears 3 supporting pointed adjustable screws 4 which are adapted to engage pointed recesses 5 in the opposite sides of the lower enlarged portion 7 of the needle arm. The enlarged portion 7 is provided with an 80 extension 10 having connection in known manner at its upper end with the diaphragm of the sound box 2.

The enlarged part or portion 7 of the needle arm is provided with a longitudinal slot 85 11 which extends throughout the length of said enlarged part as shown and which extends transversely of the said part or portion to a line substantially coincident with the longitudinal central axis of said part 7. 90 However, the depth of the said slot may vary, so that the bottom thereof is not in coincidence with the longitudinal central axis of said part or portion, without departing from my invention.

95 The lower end of the needle arm is tapered and terminates in a sharp or fine pointed portion as indicated at 13 so that if it should contact with a record 15 by reason of the wearing down of the stylus or 10 needle 16 or for any other reason said record will not be injured thereby. On the contrary such sharp or fine point will follow the sound groove in the record reproducing the sounds as though the stylus or needle were 10 present. Although in the specific construc-

tion illustrated it is intended that a stylus or needle such as 16 shall at all times be employed in connection with the needle arm for engagement with the grooves of sound records it may happen that it would be desirable to operate a machine when there is no stylus or needle to be had in which case a combined needle arm and stylus such as is illustrated by me and which may be used independently of a needle or stylus would be of great advantage.

The intermediate portion of the enlarged part 7 of the needle arm is tapered and screw-threaded as indicated at 20 for the reception of an internally screw-threaded and tapered clamping nut 21.

The slot 11 is of such width that while an attenuated stylus or needle 16 will fit the same closely it may be freely moved longitudinally therein so that it may be adjusted to cause variations in the length of the portion projecting beyond the sharp end 13 of the needle arm.

For the purpose of adjusting the attenuated or fine stylus or needle 16 longitudinally in the slot 11 I have provided a revolute adjusting wheel 24 which is mounted in bearings 25 at the front side of the enlarged portion 7.

An enlarged slot or notch 26 is provided at the upper end of the enlarged portion 7 in which the said revolute adjusting wheel is situated. The periphery of said wheel is milled or otherwise roughened and occupies a position adjacent to the bottom of the slot 11. The said periphery contacts with the stylus or needle 16 with such pressure as may be necessary to create sufficient friction between the peripheral surface thereof and the said stylus or needle to cause the latter to move longitudinally when the said wheel is rotated.

The wheel 24 is provided with marks 27 or other indicia which coöperate with a mark 28 upon the sides of the bearings 25 to indicate the extent of rotative movement imparted thereto and consequently the extent of longitudinal movement imparted to the stylus or needle 16. It is possible, therefore, to determine with exactness the length of the portion projecting below the lower end of the needle arm. It, therefore, becomes practicable for one who is unskilled to correlate the length of the projecting portion of the stylus or needle to the tone which it is desired to produce.

When it is desired to insert a stylus or needle 16 into the slot 11 the clamping nut 21 is loosened so as to permit the portions of the enlarged part 7 upon opposite sides of said slot to spring apart. The stylus or needle having been inserted the clamping nut is then screwed tight, considerable force being employed, so as to move the said portions upon opposite sides of the slot toward

each other and thereby firmly clamp the same against the said stylus or needle throughout the entire extent of the said slot whereby there can be no movement of the said stylus or needle within the bounds 70 of the clamping region independently of the needle arm itself.

By adjusting the attenuated stylus wire or needle 16 so as to vary the length of the portion thereof which projects beyond the lower end 13 of the needle arm the tone and character of the sounds emitted by the machine may be varied as already stated. By lengthening the said projecting portion the tones may be softened and by shortening the same 80 the tones may be rendered louder, ringing and more vibrant.

The stylus or needle may be constructed of any suitable hard material, such, for instance, as vanadium steel, and in view of 85 the fact that the same is in the form of an attenuated wire it may be used over and over again as stated upon the same record or different records without injury to the grooves therein.

When the end of the stylus or needle 16 has worn off so that the portion projecting beyond the lower end 13 of the needle arm is shorter than it should be the same may be adjusted in the manner above described 95 to provide a projecting portion of the length required or desired. Such adjustments may be effected from time to time as may be necessary until finally the stylus or needle is worn away to such an extent that it is too 100 short to be satisfactorily employed. While a stylus or needle too short to reach to the adjusting wheel 24 may be employed it is desirable that the same shall be of sufficient length to extend to or beyond said wheel in 105 order that it may be adjusted.

It will be seen that by my construction I am enabled to employ successfully an attenuated wire as a stylus or needle by reason of the fact that I also clamp and hold the 110 same throughout the entire length of the portion of the needle arm which directly clamps and supports said stylus or needle that it is not permitted to vibrate within the clamping region independently of its 115 support. The result of this is that only the vibrations of the stylus or needle due to the presence of its lower end within the groove of a sound record are transmitted to the sound box in consequence of which only the 120 vibrations caused by the groove itself are reproduced as sounds by the machine. I have also provided a construction in which the clamping jaws for holding the said attenuated stylus or needle wire are integral 125 with each other and in which the bottom of the slot 11 is rounded to receive the cylindrical stylus or needle wire 16. Further I have provided a construction in which a needle arm and needle are combined in a 130

single member, the sharp, pointed end of said arm serving as a stylus or needle to enter and follow the grooves of sound records.

5 I claim:—

1. A needle arm comprising a part having integral clamping jaws arranged in substantial parallel relation to each other, the said jaws being formed by a slot extending part 10 way only through and longitudinally of said part, the said part having a tapered screw-threaded portion, a clamping nut having screw-threaded engagement with said screw-threaded portion, adjustment of the said 15 nut in one direction causing adjustment of the said clamping jaws toward each other to clamp and hold a stylus or needle wire situated between said jaws.
2. A needle arm for sound reproducing 20 machines comprising a portion having a slot extending part way only through the same and from end to end thereof, the opposing surfaces of which slot are adapted to be moved into clamping relation with respect 25 to each other, a stylus or needle wire situated in said slot, means supported upon said needle arm and being in engagement with said wire for adjusting the latter, and means for causing the parts of said needle

arm on opposite sides of said slot to be 30 moved into clamping relation with respect to each other.

3. A needle arm comprising a portion having a slot extending longitudinally thereof throughout its entire length said slot extending only part way through the said portion, a stylus or needle wire situated in the bottom of said slot, and means for moving the parts of said arm upon opposite sides of said slot toward each other to 40 clamp the said stylus or needle wire.

4. A needle arm for sound reproducing machines comprising an enlarged lower end portion having a slot extending throughout the entire length of said enlarged portion 45 said slot extending only part way transversely through the said enlarged lower end portion, the lower end of said enlarged portion being provided with a sharp point in alignment with the bottom of said slot, a 50 stylus or needle wire situated in the said slot, and means for securing the said wire therein.

In testimony that I claim the foregoing as my invention I have hereunto signed my 55 name this 9th day of March, A. D. 1916.

WALTER L. ECKHARDT.
